United States Patent Office

Des. 177,454
Patented Apr. 10, 1956

177,454

CHAIR

Stanley G. Young, Long Beach, Calif., assignor to Frank Bros., Inc., Long Beach, Calif., a corporation of California

Application July 11, 1955, Serial No. 36,914

Term of patent 14 years

(Cl. D15—1)

FIG. 1

Figure 3 is a front perspective of said chair; and

I claim:

The ornamental design for a chair, substantially as shown.
